UNITED STATES PATENT OFFICE.

GEORG RESPONDEK, OF BERLIN-HALENSEE, GERMANY, ASSIGNOR TO GENERAL ELECTRIC COMPANY, A CORPORATION OF NEW YORK.

AMPLIFIER CONNECTION.

Application filed July 15, 1924, Serial No. 726,200, and in Germany September 12, 1923.

My present invention relates to amplifier connections adapted for use in long distance telephone lines.

In the connection of the coil circuits in a duplex telephone circuit with intermediate amplifiers the apparent resistance of the two lines connected by the intermediate amplifiers or the apparent resistance of each of the lines and the artificial reproduction of the same must be carefully equalized with reference to frequency. If this is not done back coupling takes place so that a disturbing whistling of the amplifier is heard, whenever a certain degree of amplification is exceeded.

It is not possible in practice to obtain the equalization between the apparent resistance of the coil circuits and their artificial reproduction for all frequencies. As shown by theory and practice, the difficulties of reproduction are especially great in the neighborhood of the natural frequency of the coil circuits.

The object of my present invention, which is an improvement over that described in a copending application of Friedrich Gehrts, Serial No. 661,739, filed September 10, 1923, is to provide means whereby the difficulties of producing the desired equalization are reduced to a minimum. In carrying my invention into effect, I provide in the amplifier connections suitable connecting impedances which are automatically variable in accordance with the direction of conversation in such a way that the development of a disturbing auto excitation is avoided, especially within the range of frequencies in the neighborhood of the natural frequency of the coil connections. The means for obtaining such results may be a choke coil the inductance of which is kept small by premagnetization which may be compensated by a counter magnetization which becomes effective at the moment talking is started in the other direction. The counter magnetization may be obtained by means of a direction amplifier or similar rectifying arrangement. While a choke coil is the preferred form of impedance, variable condensers or resistances may also be used if desired.

The novel features which I believe to be characteristic of my invention are set forth with particularity in the appended claims. My invention itself, however, both as to its

organization and method of operation will best be understood by reference to the following description taken in connection with the accompanying drawing in which I have indicated diagrammatically one way whereby my invention may be carried into effect.

I have indicated in the drawing a duplex connection for two lines F_1 and F_2 to each of which is connected an artificial line K_1 and K_2 . For each talking direction there is provided an amplifying tube V_1 and V_2 , and there is also connected to each line a direction amplifier R_1 and R_2 . The choke coil D_{R_1} which is inserted in the line F_1 V_1 F_2 may have its initial magnetization adjusted by means of a separate source of current and a special winding. This however is not necessary as the initial magnetization may be provided by means of the current in the output circuit of direction amplifier R_1 , which is supplied to the winding T_1 . The talking currents arriving over the line F_1 are supplied on the one hand to the grid circuit of amplifier V_1 and on the other hand to the coil 1 in the grid circuit of direction amplifier R_1 . The talking currents are amplified by the direction amplifier R_1 and the amplified currents supplied therefrom to the winding T_1 vary the magnetization of the core of coil D_{R_1} in the desired manner. At the same time the amplifier V_1 transmits the amplified talking currents through the windings W_1 and X_1 of coil D_{R_1} to the outgoing line F_2 . These talking currents now produce at the same time in conjunction with the current supplied to winding T_1 a change in the choking limits of the coil for the critical frequency range.

In the copending application of Friedrich Gehrts referred to above, the input circuits of the direction amplifiers were connected across the telephone lines. Because of this, the direction amplifiers were also affected by the amplified currents and a back coupling was produced which might cause a disturbing whistling. Choke coils D and condensers C were provided for the elimination of such effects.

In the present case this difficulty is avoided by connecting the grid circuits of the direction amplifiers in series with the telephone lines. The grid coils may be connected to the equalization connection of the telephone line or the input circuits of the

direction amplifiers may themselves be formed as equalizing connections $A U_1$ and $A U'_1$, as indicated, or $A U_2$ and $A U'_2$, as shown by dotted lines.

5. By reason of this connection, the talking current acts on the grid of direction amplifier R_1 in the same manner that it acts on the grid of speech amplifier V_1 so that the connection is free from any back coupling 10 and the choke coils D are no longer essential.

The operation of the direction amplifier R_2 , the speech amplifier V_2 and coil D_{R_2} for speech current coming from the line F_2 is the same as that described for the corresponding elements which are actuated by speech coming from the line F_1 .

What I claim as new and desire to secure by Letters Patent of the United States, is:

20. 1. The combination in a duplex telephone amplifier system of an incoming line and an outgoing line, an amplifier for amplifying a portion of the currents received over the incoming line and delivering amplified currents to the outgoing line, an impedance connected in the outgoing line, a second 25 amplifier having its input circuit connected to the incoming line by an equalizing connection so that it will be actuated only by incoming currents and means for controlling the value of said impedance by the current in the output circuit of the second 30 amplifier.

25. 2. The combination in a duplex telephone amplifier of an incoming line, an artificial line connected to the end of said incoming line, an outgoing line, means for amplifying a portion of the currents received over the incoming line and delivering amplified currents to the outgoing line, an impedance

40 connected in the outgoing line, an amplifier having a coil in its input circuit connected in series relation to said incoming line and artificial line, and means controlled by the current in the output circuit of said amplifier for varying the value of said impedance. 45

3. The combination in a duplex telephone amplifier system of a pair of amplifiers having their input circuits connected to a telephone line by equalizing connections so that they will be actuated only by currents received over said line, one of said amplifiers being connected to deliver amplified currents to an outgoing line and the other of said amplifiers being connected to control the impedance of the outgoing line. 50

4. The combination in a duplex telephone amplifier system of an incoming line and an outgoing line, an amplifier for amplifying a portion of the currents received over the incoming line and delivering amplified 60 currents to the outgoing line, an iron core inductance connected in the outgoing line and a second amplifier having its input circuit connected to the incoming line and having in its output circuit a magnetizing winding surrounding the core of said inductance, said amplifier being so adjusted that the normal current in its output circuit produces a predetermined desired magnetization of 65 said core and the modified current in the output circuit when speech current is received over the incoming line produces a change in the magnetization of the core and thereby varies the value of the inductance in a desired manner. 70

In witness whereof, I have hereunto set my hand this 16th day of April, 1924.

GEORG RESPONDEK.
